Assistant Examiner — Jennifer L Watkins

(57) **CLAIM**

The ornamental design for a shoe tree for drying shoes, as shown and described.

DESCRIPTION

The patent or application file contains at least one drawing executed in color. Copies of this patent or patent application publication with color drawing(s) will be provided by the Office upon request and payment of the necessary fee.

1. Shoe tree for drying shoes

1.1 : Perspective

1.2 : Left

1.3 : Front

1.4 : Perspective

1.5 : Back

Shoe tree especially for water sports and surfer's shoes, whereby the shoe tree is only inserted in the shaft diameter of the back part of the shoe supporting the complete shaft height; hereby the shaft diameter is stretched and by the shoe tree's design the circulation of the air is improved and the drying time is speeded-up; further such a shoe tree serves as a shoe rack allowing to position the shoes upside-down on a radiator or next to any other heating element securing an optimal air circulation for the shoe drying.
